UNITED STATES PATENT OFFICE.

CHARLES B. HOFFMANN, OF CINCINNATI, OHIO.

REPULSION-MOTOR-CONTROL SYSTEM.

1,078,439.

Specification of Letters Patent. Patented Nov. 11, 1913.

Application filed June 19, 1911. Serial No. 634,065.

To all whom it may concern:

Be it known that I, CHARLES B. HOFFMANN, a citizen of the United States, and a resident of Cincinnati, in the county of 5 Hamilton and State of Ohio, have invented certain new and useful Improvements in a Repulsion-Motor-Control System, of which the following is a specification.

The invention relates to electrically operated block signaling systems, more particularly those operated through the agency of an alternating electric current.

The invention has particular reference to systems in which a track is divided into 15 blocks of suitable length, insulated from one another, and in which at the beginning of each of said blocks suitable semaphore signals are provided, the signal arms of which are arranged to be power driven, that is to 20 say, by means of an alternating current motor.

The invention has for its object the control of the said motor for operating the semaphore arms, more particularly to effect 25 a "power hold-clear" as well as a "power return" of the semaphore arms.

The nature of the invention will be best understood when described in connection with the accompanying drawings, in 30 which—

Figure 1 is a diagrammatic view illustrating the general arrangement of the various circuits for a "power hold-clear" and "gravity return" system. Fig. 2 is a fragmentary diagrammatic view illustrating a modification in the "hold-clear" arrangement. Fig. 3 is a similar view illustrating the arrangement for a "power hold-clear" and "power return", and operated through 40 two auxiliary brushes. Fig. 4 is a similar view illustrating a "power hold-clear" and "power return" operated with but one auxiliary brush. Fig. 5 is a fragmentary diagrammatic view illustrating a modification in the manner of operating the motor. Fig. 6 is an elevation of the motor controller and driving gear for operating a semaphore arm.

Similar characters of reference designate 50 corresponding parts throughout the several views.

Referring now to Fig. 1 of the drawings, 20 and 21 designate the track rails which are

insulated from one another by suitable insulation 22, providing blocks 25, 26, 27, etc., 55 of suitable length. A train 28 is assumed to be located on the block 27 and to be traveling in the direction indicated by the arrow. Semaphores 30, 31, 32, etc., of well-known type, are located at the beginning 60 of each of the corresponding blocks 25, 26, 27, etc.; and their respective arms 33, 36, 37, etc., are normally inclined to the vertical at an angle of 30°, which position designates a "safe" condition of the corresponding 65 block (as in the case of blocks 25 and 26). To assume a horizontal or "danger" position (as is the case of arm 37), the arms are obliged to rotate downwardly 60°. This downward movement is usually effected by 70 gravity, as in the arrangement shown in Fig. 1; but the present invention contemplates also a positive or "power return" of this arm to the "danger" position.

Suitable mains 40 carrying alternating 75 current are arranged along the tracks and supply, through transformers 41, 42, and 43, etc., provided respectively with double secondaries 44, 45; 46, 47; and 48, 49, etc., the power for the usual track relays 50, 51, 80 52, etc., of the corresponding blocks, as well as the power for the operating motors 53, 54, 55, etc., of the corresponding semaphores. The signal relays are of the well-known type and their connections are made 85 in the usual manner, as shown, and need no further explanation.

The motors 53, 54, 55, etc., employed to operate the corresponding semaphore arms 33, 36, 37, etc., are of the "repulsion" type. 90 Such motors consist usually of a stationary primary member or stator and a rotatable secondary member or rotor, the latter being in the nature of a direct current armature, upon the commutator of which rest brushes 95 in positions 180 electrical degrees apart and directly short-circuited upon themselves. These brushes are displaced a given angle from the line of polarization of the primary magnetism. For the purposes of 100 the present invention, however, the power may be directly applied across the brushes of the rotor and the stator short-circuited, as illustrated in Fig. 5. The brushes themselves may, furthermore, be of 105 considerable width, as shown in Fig. 1, to

short-circuit a plurality of armature windings. The usual form of brush, however, is that illustrated in Figs. 2 to 5, the same being of a width equal to or less than a 5 commutator segment.

The actuating mechanism for the semaphore arms is of the well-known type, as illustrated in Fig. 6; and consists of a shaft 60 driven through an intermediate train of 10 gearing 61 from the shaft 60' of a motor 53 which is mounted in a suitable casing 62. Shaft 60 rotates in suitable bearings provided by the casing 62, and carries in addition to the arm 35 a circuit controlling device 15 63, having contact pieces 163, partaking of the motion of said shaft and semaphore arm 35. This controlling device is of the usual and well-known type (the electrical connections to which, however, have not 20 been shown) adapted to close and open in the usual manner due to its oscillation, the various electrical circuits as will hereinafter be set forth. The pinion 64 on shaft 60 and of the train gearing 61 is preferably made 25 segmental, and is provided with a pin 65 to engage a limiting stop 66 secured to the casing.

In Fig. 1, the motors 53, 54, 55, etc., are of the type with short-circuited brushes 68 30 and 69, which brushes are of considerable width and the field or primary 70 is connected through the corresponding relays 50, 51, 52, etc., with the source of power from mains 40.

When a relay is open, due to the short-circuiting of the same, as in the case of relay 52, through the wheels of a train on a corresponding block, the primary circuit of the motor is opened and the corresponding 40 semaphore arm 37 drops under the action of gravity to the horizontal position shown. This movement of the semaphore arm correspondingly operates the circuit controlling device, which moves therewith to close the 45 contact 73 through which the brushes 68 and 69 of the motor 55 are short-circuited. This condition is maintained until the block is again clear, when the relay closes. Power will then be restored to the primary 70, 50 causing the motor to operate, for the brushes will be short-circuited through switch 73 until the semaphore has been elevated, for example 58°. At this point, the circuit controller which has moved with the corresponding 55 semaphore arm will have opened the brush circuit through the switch 73, for example as in the case of switches 71 and 72. The momentum of the upwardly moving semaphore arm will carry the same a few degrees farther to its safe position—30° from the vertical, or 60° from the horizontal, the movement being arrested by the pin 65 and stop 66. This slight additional movement, however, has opened the brush 60 circuit and the semaphore arm will, there- 65

fore, naturally tend to move downwardly until the circuit were again closed. To prevent such downward movement of the arm, except when the primary circuit is opened through the relay 52, and to hold the semaphore arm in elevated and "safe" position, the brushes 68 and 69 are designed to be of considerable width so as to span a number of commutator segments. Thus, when the brush circuit is open through switch 73, 70 enough armature windings will be short-circuited by the said brushes to provide a sufficient holding torque of the motor to overcome the counter torque of the semaphore arm tending to cause the same to return 75 to a horizontal position. The semaphore arm will thus be held in elevated or "safe" position until power is cut off from the motor, as for example by the opening of the primary circuit through its relay when a 80 train is on the corresponding block. The arm then drops under the action of gravity to a horizontal or "danger" position, as explained, and remains in this position until the train has cleared the block to cause the 85 relay to close the primary circuit.

In place of the wide brushes, the same effect may be secured by means of an additional brush 75, Fig. 2, coöperating with the brushes 76 and 77, which brushes as well as 90 brush 75 are of the usual width, viz: slightly less than the width of a commutator segment. In this embodiment, an additional switch 78 is required, the same being adapted to be closed by the circuit controller after 100 the arm has moved upwardly 58°, that is to say that at the same time that the brush circuit is opened at switch 73. Switch 78 in closing, short-circuits the armature windings included between the brushes 76 and 75 and 105 produces thereby the required holding torque to maintain the semaphore arm in its elevated position.

In many instances it is desirable to return the semaphore arm to "danger" position by power and not depend on the gravity action merely; for it may occur that the arm will freeze in its elevated position and therefore will not respond when the train is in the corresponding block. To accomplish this, an additional brush 80, Fig. 3, is required as well as additional switch 81. The relay 52 is, also, provided with additional contacts 82, 83, and 84. The same result may also be accomplished by means 110 of the single additional brush 75, provided certain variations in the circuit are effected.

In case two additional brushes 75 and 80, Fig. 3, in addition to the usual brushes 76 and 77, are employed to effect the "hold-clear" and "power return" of the semaphore arm, lower contacts 83 are provided in connection with relay 52 to close the primary circuit also during the deenergized 115 condition of the said relay. A switch 81, 120

however, is included in this additional circuit for closing the primary circuit, and is adapted to be closed through the action of the controller after the arm has moved upwardly 5°. Upon the downward movement of the arm and under the power actuation, the power will thus be maintained up to within 5° of the horizontal or "danger" position. When this point is reached, switch 81 is opened and opens thus the primary circuit, the semaphore arm, however, continuing to the horizontal position under its own momentum. Upon the upward movement of the arm when the block is clear, the 15 "power hold-clear" is effected in precisely the same manner as in the embodiment set forth in Fig. 2, the circuit, however, having included therein the relay contact 82 which is closed so long as the block is clear. When 20 the relay is deenergized, Fig. 3, that is to say when a train enters the corresponding block, the contact 84 of said relay is closed and short-circuits thereby the windings of motor 55 included between the brushes 76 25 and 80. This will produce a reverse torque on the motor and thereby lower the semaphore arm to horizontal position, the motor being rendered inoperative through opening of switch 81 when the arm is within 30 5° of its "danger" position.

In the embodiment set forth in Fig. 4, a contact 84 short-circuits the armature windings of motor 55 included between brushes 75 and 77 to effect the desired reverse torque 35 for the purpose of returning the semaphore arm to its "danger" position. Brush 80 is omitted, being unnecessary in view of the short-circuiting of the armature windings between brushes 75 and 77 to produce the 40 reverse torque.

In Fig. 5 the rotor 85 of motor 55, instead of the stator 86, is made the primary of said motor, power being led to the same through brushes 87 and 88 arranged 180 electrical 45 degrees apart. The switching mechanism is otherwise precisely the same as that described in connection with Fig. 4 for effecting a "power hold-clear" and "power return" of the semaphore arm. Instead of 50 short-circuiting the various number of armature windings, however, as in the embodiment set forth in Fig. 4, corresponding turns of the field winding or stator 86 are arranged to be short-circuited.

The system herein set forth for operating the semaphore arms by means of a repulsion motor greatly simplifies the necessary mechanism, in that such devices as centrifugal governors, springs, cams, ratchets, choke 55 coils and the like may be dispensed with and the contacts on the drum controller reduced in number. Furthermore, the brushes may be set to the best operating position and the maximum effect obtained. Less actual 60 power is required to "hold clear" with the

system hereinbefore described and there is less heating of the motor. For the "power return" no special auxiliary windings are necessary on the motor, as well as no phase splitting device or outside resistance or reactance to limit the current. The only additional part is the extra brush and holder which can be put on at practically no cost and will serve for both "hold-clear" and "power return." These devices can easily 75 be installed in systems already in operation without involving any great expense or disturbing the operation.

I claim:—

1. The combination with a repulsion motor; of means to control the circuit of one of the elements of said motor; and means controlled by the movement of the rotor of said motor to vary the electrical connections of the other of said elements to hold the rotor in predetermined position. 80
2. The combination with a repulsion motor; of means to control the circuit of one of the elements of said motor; and means controlled by the movement of the rotor of said motor to vary the electrical connections of the short-circuited element to hold the rotor in predetermined position. 90
3. The combination with a repulsion motor; of means to control the circuit of one of the elements of said motor and means controlled by the movement of the rotor of said motor to open the short circuited element of said motor. 95
4. The combination with a repulsion motor; of means to open the short circuited element of said motor; and means to short circuit a predetermined number of coils of the said short circuited element to hold the rotor of the motor in predetermined position. 100
5. The combination with a repulsion motor; of means to open the short circuited element of said motor; a normally open auxiliary circuit connected with said short circuited element; and means operated by the movement of the rotor of said motor to close the said auxiliary circuit. 110
6. The combination with a repulsion motor; of means to open the short circuited element of said motor; a normally open auxiliary circuit intermediate of the short circuited connection of said motor; and means operated by the movement of the rotor of said motor to close the said auxiliary circuit. 115
7. The combination with a repulsion motor, having two brushes one hundred and eighty electrical degrees apart and normally connected together; of means to open said connection; a brush intermediate of said two brushes; and means to connect said brush with either of the said normally short circuited brushes. 120
8. The combination with a repulsion motor, having two brushes one hundred and 130

eighty electrical degrees apart and normally connected together; of means to open said connection; a brush intermediate of said two brushes; and means operated by the movement of the rotor of said motor to connect said brush with either of the said normally short circuited brushes.

Signed at Rochester in the county of Monroe and State of New York this 16th day of June A. D. 1911.

CHARLES B. HOFFMANN.
